CLAIM

The ornamental design for a noise eliminator, as shown and described.

DESCRIPTION

FIG. 1 is a perspective view of a connector housing for a noise eliminator showing our new design;

FIG. 2 is a front elevational view thereof;

FIG. 3 is a right side elevational view thereof, the left side elevational view thereof being a mirror image;

FIG. 4 is a top plan view thereof;

FIG. 5 is a bottom plan view thereof;

FIG. 6 is a rear elevational view thereof;

FIG. 7 is a cross-sectional view thereof taken along line 7—7 of FIG. 2;

FIG. 8 is a cross-sectional view thereof taken along line 8—8 of FIG. 2.
